UNITED STATES PATENT OFFICE

150,211

DESIGN FOR A STEREOSCOPIC INSTRUMENT

Charles E. Crandall, Meadville, Pa., assignor to
Keystone View Company, Meadville, Pa., a cor-
poration of Pennsylvania

Application May 20, 1947, Serial No. 139,158

Term of patent 14 years

(Cl. D57—1)

To all whom it may concern:

Be it known that I, Charles E. Crandall, a citizen of the United States, residing at Meadville, Crawford County, Pennsylvania, have invented a new, original and ornamental Design for Stereoscopic Instruments, of which the following is a specification, reference being had to the accompanying drawing, forming part thereof.

The figure is a side perspective view of a stereoscopic instrument showing my new design, the opposite side presenting substantially the same appearance as the side shown.

I claim:

The ornamental design for a stereoscopic instrument, as shown and described.

CHARLES E. CRANDALL.
